CLAIM

The ornamental design for an electric connector as shown and described.

DESCRIPTION

FIG. 1 is a front top perspective view of an electric connector showing my new design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof; and,
FIG. 8 is a rear bottom perspective thereof.

1 Claim, 8 Drawing Sheets
